UNITED STATES PATENT OFFICE

WILLIAM MATAYA, OF SEATTLE, WASHINGTON

COMMUTATOR ACCESSORY

Application filed February 15, 1928. Serial No. 254,547.

This invention is directed to an improvement in commutator cleaners and consists generally in means for wiping a commutator in order to prevent the accumulation of material tending to interfere with the brush contact.

The primary object of the invention is the provision of means in the form of a cleaner carried by the brush ring or frame and which is independently adjustable therein to compensate for wear and to insure the proper cleaning function.

The invention is illustrated in the accompanying drawings, in which:

Figure 1 is a view in elevation, partly in section, illustrating the application of the improvement.

Figure 2 is a transverse section of the cleaning element and its mounting.

Figure 3 is a similar section taken at right angles to that of Figure 2.

For the purpose of illustration, the improvement is shown as applied to a conventional machine wherein 1 indicates the commutator, 2 the field windings, 3 the rings, 4 the usual casting for supporting the brushes and which is part of the frame 5 and 6 the rod supported on the casting 4 and carrying through a suitable mounting the usual brushes 8 and conducting wires 7.

The improved cleaner is mounted upon a shaft 9 which is rotatably supported in the casting 4 and which beyond the casting is diametrically perforated to receive a stem 10 held in adjusted position diametrically of the shaft 9 by lock nuts 12. The stem 10 is insulated by insulating strips 11 and an insulating lining 13 in the opening in the shaft 9.

Carried by the lower end of the stem 10 is a holder 14 comprising a hollow sheet metal box-like construction open at the lower end to receive the cleaning element shown in the form of bristles 15 which may, if desired, be of any appropriate character.

The lower free edges of the holder 14 are slightly inturned, and a screw 16 is passed through the opposing walls and appropriately threaded in one or the other to insure a

clamping cooperation of the walls of the holder and the cleaning element.

It is well known that commutator brushes are not of the full width of the rings and therefore these brushes do not serve as a rule 55 to maintain the commutator clean, particularly beyond the area with which the brushes contact. There is, therefore, a tendency for the accumulation of dust and dirt upon this free portion of the commutator which, if permitted to accumulate, will reach the brush area and interfere with the connection.

The cleaning element 15 is of a width to include this portion of the commutator not reached by the usual commutator brushes and 65 serves to insure a wiping cooperation with such commutator throughout practically its full width to thereby maintain the same clean under all conditions. Obviously, the cleaner 15 may be adjusted relatively to the commutator through adjusting the stem 10 by the lock nuts 12, and furthermore the shaft 9 may be rotated at will to insure a proper bearing of the cleaning element upon the 70 commutator.

What is claimed to be new is:

1. In combination with a commutator and a brush holding casting cooperating therewith, of a cleaning element to cooperate with the commutator and including a shaft rotatably mounted in said casting, a holder adjustable diametrically of the shaft, and a series of bristle elements secured in the holder.

2. In a dynamo electric machine having a commutator and a brush holder support, the combination of a shaft rotatably mounted in said support, a stem carried by the shaft, the said stem being vertically adjustable with relation to the shaft, and a brush carried on the end of the stem, the said brush contacting 85 with the face of the commutator and thereby cleaning the same.

In testimony whereof I affix my signature.

WILLIAM MATAYA.
